AUTOMATIC SEAMLESS HOSIERY MACHINE

Shuji Kakigahara, Ikegami-Machi, Ebara-Gori,
Tokyo-Fu, JapanApplication August 14, 1930, Serial No. 475,226,
and in Japan August 29, 1929

4 Claims. (Cl. 66—43)

This invention relates to improvements in automatic seamless hosiery machines, and concerns more particularly a device for knitting the foot part of ladies' hose of the split foot type with an inturned knitted welt and has for its object to provide an improved device for knitting the foot part of ladies' hose of the above mentioned kind so constructed as to be readily applied to a Scott and William model K machine 10 with only a slight change in the existing machine.

According to one feature of the invention, the instep and sole parts of the foot part of the hose can be knitted from different yarns.

According to another feature of the invention, 15 cut floating yarns presenting an awkward appearance are entirely dispensed with and there is no floating yarn waste.

According to another feature of the invention, the device is automatically operated and adapted 20 to produce hose of high class.

According to another feature of the invention, the machine provided with the device produces perfect hose regardless of whether the gauge or stitch length is small or large.

According to another feature of the invention, 25 the splice between the sole and instep parts of the hose makes two parallel straight lines to present good appearance.

According to another feature of the invention, 30 the yarns used for knitting the inside of the sole part of the hose do not appear on the outside of the hose.

According to a further feature of the invention, the adjustment of the stitch of the sole part of the 35 hose is rendered easy.

According to a still further feature of the invention, any small defect is avoided in the splicing of the ankle and sole part of the hose, when the splicing yarns pass through.

In connection with the application of this invention to a Scott and Williams K model machine, it is to be noted that the existing pattern drum of Scott and Williams model K machine is provided with four additional drum cams 48, 45 only one of which is shown, of special form for actuating the push bars 37, 38, 39 and 40 as will hereinafter be described, the clutch shipper cam (not shown) secured to the clutch shipper drum (not shown) is made in a shape adapted to give 50 the needle cylinder 42 reciprocating rotation in such a manner that it makes a round turn in one direction and then a similar turn in an opposite direction during the knitting of the foot part with the exception of the ring toe part of the hose, 55 as it may be the case when knitting the heel and

toe parts of the hose, instead of making continuous rotation in one direction, and a device is provided for bringing the existing cylinder jack (not shown) in its inoperative position during the reciprocating rotation of the needle cylinder 42. 60

In the accompanying drawings:

Fig. 1 is a front elevational view of a machine to which the invention is applied.

Fig. 2 is a left side elevational view of Fig. 1.

Fig. 3 is a perspective view of essential parts of the invention drawn to an enlarged scale. 65

Fig. 4 is a side detail view of the parts of the invention as shown in Fig. 3 taken from the left side thereof and drawn to an enlarged scale. 70

Fig. 5 is a plan view of Fig. 4.

Referring to the drawings, the bed plate 1 is near its fore edge formed with a recess 1' which permits a slide member 3 to move through the bed. A guide member 2 for the slide member 3 is secured to the bed plate 1 at its under side and below the recess 1' and is provided at one side edge with a slot 6 for a guide pin 5 secured to the corresponding side edge of the slide member 3. On the slide member 3 is secured a block 4, the upper face of which is of a substantially trapezoidal shape as shown. A bracket 7 is secured to the flat top of the block 4 and carries a guide member 9 by means of a rod 8, which guide member has substantially V-shaped ends 9' and inverted V-shaped notches 9'' at the under side adjacent the V-shaped ends and normally engages with the needle cylinder 42. On the inclined upper faces of the block 4 there are fixed pins 12, on each of which is rotatably mounted a down picker 10. The down pickers are tensioned to normally lie with their heads below the respective inverted V-shaped notches 9'' of the guide member 9 by means of springs 13 encircling the pins 12, one end of each spring being secured to the lower part of the pin, and the other end secured to the eye end of the stem 11 of the down pickers 10. The block 4 is formed at its flat top and under the bracket 7 with a recess 14, into which a member 15 is inserted. The member 15 is provided at the rear end with a widening pick stop 16 adapted to engage with the stem of the down pickers, and is connected at the fore end to a rod 17 which is vertically movable by the switch cam rod 19 (Figs. 1 and 2) of the existing hosiery machine through means of a connecting arm 18, the rod 17, the member 15 and the widening pick stop 16, whereby the slide member 3 may be vertically moved within the block 4. Secured to the bottom of the block 4 is a slide bed 43 on which a carriage 20 is slidably mounted. The 110

95

100

105

110

carriage is provided at the fore end with recesses 20', which are positioned beneath the notches 4' formed in end of the bottom of the block 4. The carriage 20 may be horizontally moved by an actuating bar 23 (Figs. 2 and 3) through a lever 22 pivoted at 22' and a connecting member 21 having a pin 21' engaging with a notch on one end of the pivoted lever 22, the ends of which connecting member 21 being secured to the fore end of the carriage 20. The carriage 20 as clearly shown in Fig. 3 is provided at the rear end with two oppositely disposed stitch cams 24, which are normally out of engagement with the needle cylinder 42, but which cams may be brought into engagement 10 with the cylinder 42 by the horizontal movement of the carriage 20, caused by the operation of the actuating bar 23. The slide bed 43 can be lifted and lowered with the slide member 3 by means of an actuating lever 25 pivoted at 25', the fore end 15 of which engages with the under side of the guide pin 5.

Between the stitch cams 24, there is a center cam 26, which is substantially triangular in its general outline, and has a stem 27 near an apex, 25 which is inserted in a guide-way 28, formed at the top side of the carriage 20. The center cam may be horizontally moved by an actuating bar 30, through means of a lever 29, pivoted at 29' and a pin 26' fixed to the fore end of the stem of the cam and engaged with a notch provided at one end of the pivoted lever 29, as more clearly shown in Fig. 3.

A segmental bar 32 having yarn restraining pins 31 is vertically and movably mounted in a 30 guide 44 fixed to one side of the existing latch ring 45 of the machine by a bracket 33, the lower arm of which is inserted in the guide, and the upper arm fixed to the segmental bar. The segmental bar is pulled down by spring 34 during the 35 knitting of the heel of the hose, one end of said spring being secured to a pin 33' on the upper part of the lower arm of the bracket 33 and the other end being secured to a pin 44' on the lower part of the guide 44, to permit the foot of the 40 yarn restraining pins 31 to enter the corresponding recess formed near the periphery of the dial (not shown) on the needle cylinder, the restraining pins being for the purpose of preventing the 45 yarn for knitting the instep of the foot, which is now idle, from being caught by moving parts of the machine during the knitting of the heel. The 50 restraining pins are held out of the dial recesses, when parts other than the heel of the hose are being knitted, by a lever 35 which has a lug 35', and is adapted to be horizontally moved by an 55 actuating bar 36, the lug being brought into engagement with the under side of the bracket 33, when the bar 36 is operated.

The actuating bars 23, 25, 30, 36 are connected 60 with push bars 37, 38, 39 and 40 respectively which are periodically actuated by respective cam drum 48 (only one of which is shown) provided on the existing pattern drum 41.

An additional yarn finger 46 is provided for 65 feeding yarns for knitting the sole part of the hose, which is different from the yarns for knitting the instep part of the hose, and represents a yarn change lever for controlling the feeding of the yarns. 48 presents a drum cam on the 70 pattern drum 41, 49 designates a switch cam for controlling the position of the long butt needles and 50 represents a lever actuated by a drum cam 48 on the pattern drum 41 to actuate the cylinder jack (not shown) through means of the 75 jack cam rod 51.

The other particulars of the Scott and Williams model K machine are not further shown and described, as the existing machine is well known and form no part of the present invention.

In operation, before the knitting of the leg part of the hose begins, it is to be noted that the slide bed 43 has been lifted with the slide member 3 by means of the push bar 38 through means of the actuating lever 25, the said push bar engaging at its lower end with the drum cam 48 of the pattern drum 41 (Fig. 2); the yarn restraining pins 31 have been lifted to their inoperative position by means of the push bar 40 through means of the actuating bar 36, lever 35 and bracket 33, the said push bar engaging at its lower end with the corresponding drum cam 48 on the said pattern drum 41; the center cam 26 has been brought into disengagement with the needle cylinder 42 by means of the push bar 39 through means of the actuating bar 30 and the lever 29, the said push bar disengaging at its lower end with the drum cam 48 on the said pattern drum; and at the same time the yarn finger 46 (Fig. 2) has been moved to its inoperative position by means of the lever 29 through means of the auxiliary yarn change lever 47 operatively associated therewith; the existing cylinder jack (not shown) has been brought into its operative position through means of the jack cam rod 51 and the jack cam (not shown); the down pickers 10 have been in their operative position, the widening pick stop 16 being in its upward position; the stitch cams 24 have been brought into disengagement with the needle cylinder 42, the push bar 37 engaging at its lower end with the corresponding drum cam 48 of the pattern drum; and the long butt needles have been lowered, the switch cam 49 being in its lifted position.

The leg part of the hose may now be knitted 115 in the same manner as the regular Scott and Williams model K machine. In the course of knitting the leg part of the hose and after the inturned welt is knitted, the stitch cams 24 are brought into engagement with the needle cylinder 42 by means of the push bar 37 by means of the actuating bar 23, the pivoted lever 22, the connecting member 21 and the carriage 20, the said push bar disengaging at its lower end with a drum cam 48 of the pattern drum; at 120 the same time the lever 50 engages at its one end with a drum cam 48 so that the cylinder jack is brought into inoperative position through means of the jack cam rod 51 and jack cam.

Upon the completion of the knitting of the 125 leg part of the hose, the long butt needles are lifted by means of the switch cam rod 19 through means of the switch cams 49, preparatory to knitting the foot part of the hose; the slide bed 43 is lowered to the position for adjusting the 130 stitch length or gauge of the ankle and sole parts of the hose by means of the push bar 38 through means of the aforesaid member associated therewith, the said push bar disengaging at its lower end with the drum cam; and the center cam 26 is brought into engagement with the needle cylinder 42 by means of the push bar 39 through means of the aforesaid members associated therewith, the said push bar engaging at its lower end with the drum cam and at the 135 same time the yarn finger 46 is moved to its operative position by means of the lever 29 through means of the aforesaid members associated therewith. At this time, the down pickers 10 are held down in their inoperative position 140

by means of the switch cam rod 19 through means of the connecting arm 18, the rod 17, the actuating member 15 and the widening pick stop 16.

The foot of the hose may now be knitted. It is to be noted that the needle cylinder 42 will make reciprocating rotation during the knitting of the foot with the exception of the ring toe part, in such a manner that it makes a round turn in a direction and then returning turn in opposite direction, instead of continuous rotation in a direction, due to the modification of the clutch shipper cam of clutch shipper drum (not shown) in the regular Scott and Williams model K machine. On a round turn of the needle cylinder 42 in clockwise direction, the long butt needles are lowered to cause their butts to pass on the under side of the corresponding one of the stitch cams 24 by the action of the center cam 26 to form loops, and then they are restored to their lifted position by means of the switch cam 49, and on a returning swing of the said needle cylinder in an opposite direction the long butt needles are again lowered to cause their butts to pass on the under side of the corresponding other one of the said stitch cams by the action of the center cam 26 to form loops, and then they are restored to their lifted position by means of other switch cam. In this manner, the ankle and corresponding part of the instep of the hose are knitted.

Upon knitting the heel of the hose, the center cam 26 is brought into disengagement with the needle cylinder 42, the push bar 39 disengaging at its lower end with the drum cam, and at the same time the yarn finger 46 is moved to its inoperative position; the yarn restraining pins 31 are lowered to their operative position, the push bar 40 disengaging at its lower end with the drum cam; and the slide bed 43 is lifted, the push bar 38 engaging at its lower end with the drum cam.

The heel of the hose may now be knitted. In the course of knitting the heel, the down pickers 10 are brought into their operative position by means of the switch cam rod 19 through means of the aforesaid members.

Upon the completion of the knitting of the heel of the hose, the yarn restraining pins 31 are lifted again to their inoperative position by means of the push bar 40; the center cam 26 is brought again into engagement with the needle cylinder 42 by means of the push bar 39 and at the same time the yarn finger 46 is brought again to its operative position; the slide bed 43 is lowered again to the adjusting position of the stitch length or gauge of the sole by means of the push bar 38; and the down pickers 10 are again held in their inoperative position by means of the widening pick stop 16.

The sole and corresponding part of the instep of the hose may now be knitted.

Upon the completion of the knitting of the sole, and corresponding part of the instep of the hose, the long butt needles are lowered to their operative position by lifting the switch cam 49 by means of the switch cam rod 19 and at the same time the down pickers are made operative by lifting the widening pick stop 16 by means of the said switch cam rod; the center cam 26 is brought again into disengagement with the needle cylinder 42, the push bar 39 disengaging at its lower end with the drum cam and at the same time the yarn finger 46 is moved again to its inoperative position.

The ring toe of the hose may now be knitted. During this operation, it is to be noted that the

needle cylinder 42 makes a continuous rotation in one direction.

Upon completing the knitting of the ring toe of the hose, the long butt needles are lifted by means of the switch cams 49; the yarn restraining pins 31 are lowered to their operative position, the push bar 40 disengaging at its lower end with the drum cam, as above mentioned; and the slide bed 43 is lifted, the push bar 38 engaging at its lower end with the drum cam.

The toe of the hose may now be knitted. During this operation, it is to be noted that the needle cylinder 42 makes again the reciprocating rotation, instead of a continuous rotation in one direction. In the course of knitting the toe, the down pickers 10 are restored to their operative position by the upward movement of the widening pick stop 16.

Upon completing the knitting of the toe of the hose, the yarn restraining pins 31 are lifted to their inoperative position, the push bar 40 engaging at its lower end with the drum cam; and the long butt needles are lowered to their operative position by the upward movement of the switch cams 49.

Thus, when the knitting of the hose has been completed, the stitch cams 24 are brought into disengagement with the needle cylinder 42, the push bar 37 engaging at its lower end with the drum cam, and the cylinder jack is moved to its operative position by means of the jack cam (not shown), the lever 50 disengaging at its one end with the drum cam.

I claim:

1. In a hosiery knitting mechanism, a needle cylinder having a dial with a number of recesses and independently movable needles therein, means for operating same, a horizontally reciprocable and vertically movable cam carriage, means for operating same, a needle guide member mounted on the carriage, a pair of oppositely disposed stitch cams for engagement with the needles, mounted on the cam carriage, a slidable center cam on the carriage for engagement with the needles, independent means for reciprocating same, a pair of oppositely disposed down-picks made on the carriage, and means for operating same, for use during the knitting of the heel of the hose, and a plurality of vertically movable yarn restraining pins, adapted to enter the dial recesses to restrain the yarn fed to the needles during a portion of the knitting operation, and means for operating said pins.

2. In a hosiery knitting machine, a needle cylinder having a dial with a number of recesses, and movable needles therein, a horizontally and vertically movable cam carriage on the machine, means for operating the cam carriage, a needle guide member on the carriage, a pair of oppositely disposed stitch cams on the cam carriage, the guide member and the stitch cams both being adapted to engage while in an elevated position, the needle cylinder for knitting the leg part of the hose, an independently operated slidable center cam on the carriage adapted to engage the needle cylinder for knitting the sole part of the hose, when the cam carriage is lowered in position, a pair of spring-held down-picks on the carriage for knitting the heel of the hose when the center cam is placed in a retracted position, means for independently operating the down-picks, in combination with a yarn restraining mechanism mounted on the knitting machine, comprising a segmental bar, a plurality of yarn restraining pins mounted in the bar adapted to

enter the dial recesses and restrain the yarn used for knitting the instep while the heel is being knitted, and means for operating said restraining mechanism from the moving parts of the knitting machine.

5. In a hosiery knitting machine, a needle cylinder having a dial with a number of recesses, and movable needles therein, a horizontally and vertically movable cam carriage on the machine, 10 means for operating the cam carriage, a needle guide member on the carriage, a pair of oppositely disposed stitch cams on the cam carriage, the guide member and the stitch cams both being adapted to engage while in an elevated position, the needle cylinder, for knitting the leg part of the hose, an independently operated slideable center cam on the carriage adapted to engage the needle cylinder for knitting the sole part of the hose, when the cam carriage is lowered in 20 position, a pair of spring-held down-picks on the carriage for knitting the heel of the hose when the center cam is placed in a retracted position, means for independently operating the down-picks, in combination with a yarn restraining mechanism mounted on the knitting machine, comprising a segmental bar, a plurality of yarn restraining pins mounted in the bar adapted to enter the dial recesses and restrain the yarn used for knitting the instep while the heel is being 30 knitted, an L-shaped bracket mounted on the segmental bar, a vertically disposed guide therefor mounted on the knitting machine, a horizontally disposed lever having a lug thereon adapted to slidably engage beneath the bracket arm for elevating the segmental bar, and resilient means 35 connecting the guide and the bracket, for automatically lowering the segmental bar when the lug on the horizontal lever is removed from the bracket, and means for operating said horizontal lever from the moving parts of the knitting machine.

4. In a hosiery knitting machine having a pattern drum and a down-pick actuating rod thereon, a needle cylinder having a dial with a num- 45

ber of recesses and movable needles therein, a horizontally and vertically movable cam carriage having a slotted guide-way in its upper face, mounted on the machine, providing a means for supporting and actuating a number of associated operating parts carried thereon, a trapezoidal block superimposed on the cam carriage, a needle guide member on the carriage normally adapted to engage the needle cylinder, a pair of opposed stitch cams mounted on the carriage for controlling the action of the needles; a center cam mechanism comprising a stem adapted to reciprocate in the cam carriage guide-way, a pin in the cam stem, and a vertically disposed cam-shaped head on said stem adapted to control the operation of the needles in conjunction with the action of the needle guide member, a bent lever pivotally mounted on the carriage having a recess therein adapted to engage the pin of the center cam stem, and reciprocate the center cam when the lever is actuated; operating means connecting the pattern drum with the bent lever, a pair of opposed spring-held down-picks revolvably mounted on the carriage, adapted to engage the needle cylinder during the period when the heel of the hose is being knitted, means for independently controlling the action of the down-picks from the down-pick actuating rod of the machine, means for vertically and horizontally moving the cam carriage and its associated parts from the pattern drum; and a yarn restraining mechanism, comprising a spring-actuated segmental bar mounted on the knitting machine, a plurality of yarn restraining pins mounted in the said bar adapted to enter the dial recesses and restrain the yarn fed to the needles and used for knitting the instep while the heel is being knitted, and means connecting the pattern drum with the segmental bar for permitting the automatic lowering of the segmental bar and the yarn restraining mechanism during the period of operation when the heel of the hose is being knitted.
